UNITED STATES PATENT OFFICE.

WILLIAM LAIRD BROWN, OF LANSDOWNE, PENNSYLVANIA, ASSIGNOR TO WILLIAM E. HELME AND JOHN McILHENNY, TRADING AS HELME & McILHENNY.

GAS-METER.

1,187,966.

Specification of Letters Patent. Patented June 20, 1916.

Application filed December 1, 1915. Serial No. 64,423.

To all whom it may concern:

Be it known that I, WILLIAM LAIRD BROWN, a citizen of the United States, residing at Lansdowne, in the county of Delaware and State of Pennsylvania, have invented certain new and useful Improvements in Gas-Meters, whereof the following is a specification, reference being had to the accompanying drawings.

10 My invention relates particularly to that class of gas meters that are adapted for consumers' service, and are ordinarily interposed in the pipe line between the service main and the domestic gas consuming appliances, and is directed especially to the mechanism which effects the actuation of the indicator, and specifically refers to the means for preventing the backward rotation of such mechanism.

15 Gas meters of the character above set forth ordinarily comprise a bellows by which the gas pressure effects the rotation of mechanism for actuating the indicating device, and in order to prevent the malicious 20 cheating by a dishonest consumer by reversing the connection and thereby reversing the actuation of the mechanism so as to decrease the reading of the index, said mechanism is provided with a dog or pawl, which in meter parlance is commonly termed a "click", and which is so pivotally suspended in the path of the rotatable mechanism as to permit its 25 rotation in one direction and arrest its rotation in the opposite direction.

30 As the gas in the service mains is usually of a temperature considerably lower than the consumer's service pipes, the gas entering the consumer's service pipes naturally rises in temperature and consequently expands, causing increased pressure which tends to force the gas back through the meter into the service main, and effecting a 35 backward rotation of the indicating mechanism. If the mechanism happens to be in such relation to the click when the gas is shut off at the gas consuming appliances, as to be engaged by the click, its backward movement would be prevented, and therefore 40 equalization of the pressure of the consumer's service pipes and the service main would be impossible. Such resulting difference

of pressure would effect a strain on the parts of the meter mechanism, sufficient to break or permanently deform said mechanism to such an extent that it would not pass gas 55 and thereby necessitate its removal, or the deformation might be so slight as to merely affect its accuracy.

It has been found in practice that the backward movement of the meter mechanism due to expansion of the gas in the consumer's service pipe is less than a single revolution. Therefore if said mechanism could be free to rotate backward to the extent indicated no damage could happen to the meter 60 from such expansion.

The principal objects of my invention are to obviate the difficulties above noted by providing simple and efficient means which will permit such backward rotation of the 65 meter mechanism to the extent indicated.

Other objects of my invention are to provide a click so constructed and arranged that it may be readily substituted in meters in use, without otherwise modifying the meter 70 mechanism to effect the results desired.

Specifically stated the form of my invention as hereinafter described comprehends a click having a pivoted depending balance pendulum, coöperative with a bell-crank-lever mounted to oscillate on the pivot of said pendulum and having one arm normally disposed in the path of the rotary mechanism and arranged to yield thereto in either direction of rotation of said mechanism, and the other arm arranged to be shifted by the backward rotation of said mechanism in passing said click, into position to arrest said mechanism in its second attempt to pass said click while rotating 85 backward.

My invention also includes all of the various novel features of construction and arrangement as hereinafter more definitely specified.

In the accompanying drawings, Figure 1 is a plan view of a gas meter with the top removed and showing the operative mechanism embodying a click conveniently constructed in accordance with my invention; 100 Fig. 2 is a side elevational view of the click and its coöperative mechanism *per se*; Fig.

3 is a side elevational view of the structure shown in Fig. 2, as viewed from the left of said figure; and Fig. 4 is a side elevational view, similar to Fig. 2, showing the click 5 in the position effected by the backward rotation of the coöperative mechanism and in position to prevent the further rotation of said mechanism.

In said figures the gas meter 5, which is 10 of a well known construction comprises the oscillatory flag rods 6 and 7 respectively carrying the flag arms 9 and 10 arranged to oscillate as shown by the arrows thereon, and having their free ends connected by 15 the flag links 12 and 13 with the tangent arm post 15, which is carried by the rotatable tangent arm 16 having threads 17 by which said tangent arm post 15 may be conveniently adjusted with respect to the axis 20 of rotation of said tangent arm 16 by means of the jam nuts 18.

The crank-shaft 19 upon which the tangent arm 16 is carried, is provided with a worm or spiral 20, the threads of which inter-engage the teeth of the gear wheel 21 which is mounted on the horizontal axle or shaft 22 of the index mechanism 23, whose casing affords a bearing for one end of said shaft 22 while the other end adjacent 30 to the gear wheel 21 is mounted to rotate in the bracket 25.

The mechanism thus far described is common and well known in the manufacture of gas meters and therefore it is not deemed 35 necessary to dwell upon such details or to further describe their operation except as they coöperate with the click.

The click supporting bridge 26 which is carried by the king post or pedestal 27 40 and which affords a convenient bearing for the crank-shaft 19 as best shown in Figs. 1 and 3, is provided with the transversely extended slot 29 opening toward the direction of normal rotation of the tangent arm 45 16 as shown by the arrow in said figure, and said slot has its wall 30 inclined downward toward its open end as shown in Figs. 1, 2 and 4.

As best shown in Fig. 1, the bridge 26 50 is provided with a notch or recess 32 which affords parallel bearing projections through which the arbor 33 for supporting the tangent click may extend. In the structure contemplated the tangent click is formed of 55 a balance pendulum 35 and a bell-crank-lever 36, the arbor 33 not only providing a pintle for the balance pendulum 35 but the bell-crank-lever being also carried by said arbor, thereby affording a common axis 60 upon which said balance pendulum and bell-crank-lever may independently oscillate.

As best shown in Figs. 1 and 3, the balance pendulum 35, has its upper end ex- 65 tended laterally to provide a projection 37

for engaging the arms 38 and 39 of the bell-crank-lever and thereby limiting the relative movement of said balance pendulum and bell-crank-lever, and as shown in Figs. 2 and 4 said projection extends between said arms. 70

The normal operation of the meter tends to rotate the mechanism to drive the tangent arm 16 in the direction of the arrow in Fig. 1, or anti-clockwise which tends to 75 maintain the click in the position shown in Fig. 2, except when engaged by the tangent arm 16 when it momentarily yields to permit its free rotation but is immediately returned to the position shown in Fig. 2 by 80 the balance pendulum 35, which is so formed that it will maintain the bell-crank-lever either in the position shown in Fig. 2 or in the position shown in Fig. 4. Should however, any back pressure develop in the 85 consumer's service system as above described, which would effect a backward rotation of the mechanism to cause the tangent arm to rotate in opposition to the direction indicated by the arrow in Fig. 1, or clockwise 90 from its position shown in said figure, it would engage the arm 38 and rotate the bell-crank-lever from the position shown in Fig. 2 to the position shown in Fig. 4, so that 95 said arm 38 would swing free of the path of said tangent arm as indicated by the dot and dash lines in said figure, and such movement of said bell-crank-lever would also swing the arm 39 into the path of said tangent arm and effect its arrest upon the 100 next succeeding cycle of movement, the bell-crank-lever being prevented from rotation by engagement of its arm 38 with the inclined surface 30 of said slot 29.

My invention is advantageous in that the 105 balance pendulum and bell-crank-lever are mounted to independently oscillate upon a common arbor.

Having thus described my invention, I claim:—

1. In meter construction comprising rotary mechanism, a click having a bell-crank-lever, and a balance pendulum mounted to swing independently of said bell-crank-lever and coöperative therewith tending to yieldingly maintain one arm thereof in the path of said mechanism permitting its unlimited rotation in one direction, and being oscillated by said mechanism in the first cycle of rotation in the reverse direction to shift the 115 other arm into an unyielding position to arrest said mechanism in its second cycle of rotation.

2. In meter construction comprising rotary mechanism, a click having a bell-crank-lever, and a balance pendulum mounted to oscillate upon a common axis with said bell-crank-lever, and having a projection extended between its arms, one of said arms being yieldingly retained in the path of said 125 130

mechanism thereby permitting its unlimited rotation in one direction, and permitting it to be shifted, by the reverse rotation to yieldingly pass said mechanism, to an unyielding position and presenting the other arm in position to arrest said mechanism.

5 In testimony whereof, I have hereunto

set my hand in the presence of two subscribing witnesses.

WILLIAM LAIRD BROWN.
